UNITED STATES PATENT OFFICE.

WILLIAM L. PATTISON, OF ROSEDALE, KANSAS.

FLOOR GRATING.

1,421,827.

Specification of Letters Patent.

Patented July 4, 1922.

Application filed December 12, 1920. Serial No. 431,737.

To all whom it may concern:

Be it known that I, WILLIAM L. PATTISON, a citizen of the United States, residing at Rosedale, in the county of Wyandotte and State of Kansas, have invented a certain new and useful Improvement in Floor Gratings, of which the following is a specification.

My invention relates to improvements in floor grating.

10 One of the objects of my invention is to provide a floor grating which is ornamental in appearance, which is strong and rigid and not liable to distortion, which is durable, cheap to manufacture and which is adapted 15 to have its upper and lower sides reversed, so that either of said sides may be utilized as the upper or wearing surface.

The novel features of my invention are hereinafter fully described and claimed.

20 In the accompanying drawing, which illustrates the preferred embodiment of my invention,

Fig. 1 is a perspective view of my improved floor grating.

25 Fig. 2 is an enlarged top view of a portion of the same.

Fig. 3 is an enlarged cross section on the line 3—3 of Fig. 1.

Similar reference characters designate 30 similar parts in the different views.

1 designates a plurality of parallel longitudinal bars, preferably flat bars disposed edge up. A plurality of intermediate bars are arranged alternately between and attached respectively to the adjacent sides of the adjacent parallel bars 1.

Each of the intermediate bars is provided with a plurality of obliquely disposed parallel portions 2 and cross portions 3, the cross portions 3 being at right angles and attached 40 at their ends to adjacent parallel bars 1 respectively and connecting adjacent ends of adjacent oblique portions 2.

The cross portions 3 of each intermediate bar are disposed in transverse alignment respectively with the adjacent cross portions of the adjacent intermediate bars and are attached, as by welding, to the adjacent bars 1.

50 The intermediate bars which are next adjacent to each other have their oblique portions 2 disposed or inclined in opposite directions. This construction affords a bracing effect which holds the parallel bars from 55 relative longitudinal movement with respect to each other, and the arrangement of the

cross portions at right angles to the bars 1 and in transverse alignment with the cross portions of the other intermediate bars affords a strong bracing effect against lateral thrust upon the bars 1.

The upper edges of the parallel bars 1 and the lower edges thereof are, preferably, flush with the upper and lower edges respectively of the intermediate bars. By means of this feature of construction, both upper and lower sides of the grating have smooth surfaces, and the upper and lower sides may be reversed, when one side which has been the upper or wearing side, has become worn.

I do not limit my invention to the structure shown and described, as modifications, within the scope of the appended claims, may be made without departing from the spirit of my invention.

What I claim is—

1. In a floor grating a plurality of parallel bars, and an intermediate bar having a plurality of parallel obliquely disposed portions and a plurality of cross portions disposed connecting adjacent ends of said oblique portions and attached at their ends and disposed at right angles to said parallel bars respectively, substantially as set forth.

2. In a floor grating a plurality of parallel bars, and intermediate bars disposed alternately between and attached to said parallel bars, each intermediate bar having a plurality of parallel obliquely disposed portions and a plurality of cross portions disposed at right angles and attached to said parallel bars respectively adjacent thereto, said cross portions connecting adjacent ends of adjacent oblique portions, substantially as set forth.

3. In a floor grating, a plurality of parallel bars, and intermediate bars disposed alternately between and respectively attached to said parallel bars, each of the intermediate bars having a plurality of parallel obliquely disposed portions and a plurality of cross portions at right angles and attached at their ends to the adjacent parallel bars respectively and connecting adjacent ends of said adjacent oblique portions, the oblique portions of the intermediate bars which are disposed next adjacent to each other being inclined in opposite directions, the cross portions of each bar being disposed in transverse alignment with the adjacent cross portions respectively of the other bars, substantially as set forth.

4. In a floor grating a plurality of flat parallel bars disposed edge up, and flat intermediate bars disposed edge up and alternately between and attached to the adjacent parallel bars, the upper and lower edges of the intermediate bars being flush respectively with the upper and lower edges of the parallel bars, each of the intermediate bars having a plurality of parallel obliquely disposed portions and a plurality of cross portions at right angles and attached at their ends to adjacent parallel bars respectively and connecting adjacent ends of adjacent oblique portions, the oblique portions of the intermediate bars which are disposed next adjacent to each other being inclined in opposite directions, said cross portions of each intermediate bar being disposed respectively in transverse alignment with the adjacent cross portions respectively of the other intermediate bars, substantially as set forth.
- 10 In testimony whereof I have signed my name to this specification.

WILLIAM L. PATTISON.
